WALL COVERING

Ambrose W. Herbes, Jackson Heights, N. Y., assignor to The Ruberoid Co., New York, N. Y., a corporation of New Jersey

Application June 18, 1945, Serial No. 600,049

4 Claims. (Cl. 20—5)

This invention relates to a wall covering, and more particularly to an outer wall covering or weather-boarding formed of asbestos-cement siding elements.

One of the objects of the invention is to provide an outer wall covering of asbestos-cement boards that will simulate the appearance of a clapboard siding.

Another object is to provide a covering of asbestos-cement boards that will have a heavy or accentuated shadow-line to give an illusory effect of greater thickness of the covering elements.

A further object is to provide a weather and waterproof covering that will effectively shed rain water.

A still further object is to provide a covering that is inexpensive, durable, and easy to apply.

It is also an object of the invention to provide an outer wall construction that will permit "breathing," that is to say it will allow moisture and water to escape, thus eliminating sweating of the inner walls and thereby preventing paint peeling, wall paper discoloration, and damage from rot.

Other objects and advantages of the invention will appear from the following description thereof, reference being had to the accompanying drawing in which:

Figure 1 is a front elevation, partly broken, of a section of a wall covering embodying the invention; and

Fig. 2 is a cross-sectional view taken on the line 2—2 of Fig. 1.

The wall structure comprises the usual studding 10 and sheathing 11, which latter may be of wood, composition board, or any other suitable material.

The covering elements 12 consist of flat boards of asbestos-cement, or the like, of uniform thickness throughout and of greater length than width. Usually the boards are made in lengths of 4, 6 or 8 feet by 6, 8 or 10 inches in width, and about $\frac{1}{8}$ inch thick although these dimensions may be varied.

Beginning from the ground up, battens or laths 13 of wood or the like are fastened by nails 14 to the sheathing in horizontal rows. The battens are preferably slightly thicker than the siding elements, being usually about $\frac{1}{4}$ to $\frac{1}{2}$ inch thick. The several rows of battens are spaced apart uniformly at intervals somewhat less than the width of a siding element 12.

The siding elements of each course are applied with their upper edges 15 butting against the lower face of the battens of the next upper row and they are fastened to the sheathing by nails 55

16. The lower edges 17 of the siding elements bear on and overhang the battens of the next lower row. This effects the desired cant and overlap to simulate clapboard and conceals the nail heads.

On reference to Fig. 2 it will be seen that the lower edges of the siding elements of each course are spaced slightly outward, as at 18, from the upper edges of the elements of the next lower course. This not only permits of "breathing" but also serves to cast a heavy shadow-line, represented by the shading 19, that accentuates the apparent thickness of the siding elements. The asbestos-cement siding elements are substantially 15 impervious to moisture but by reason of the relative porosity of the battens and the space between the upper edges of the siding elements of one course and the overhang of the next upper course escape of moisture and vapor from the interior of the structure is permitted. Furthermore, it will be observed that air spaces 20 are formed between the sheathing 11 and each course of siding elements that increase the installation efficiency of the covering.

25 While the several rows of battens may be secured in place before the siding elements are applied, the usual practice is to start from the base and to affix the battens of each row after the battens and the siding elements of the course 30 below have been applied.

Strips 21 of asphalt saturated felt may be applied under the butting ends of the siding elements of each course to waterproof the joints.

What I claim is:

35 1. An outer wall structure comprising a sheathing and a covering of asbestos-cement siding elements applied in courses to simulate clapboard, said siding elements being of uniform thickness and of greater length than width, battens secured to the sheathing in horizontal rows at intervals slightly less than the width of a siding element, the siding elements of each course having their upper edges butting against the battens of the next upper row and having their lower edges resting directly on and overhanging the battens of the immediate lower row.

40 2. An outer wall structure comprising a sheathing and a covering of asbestos-cement siding elements applied in courses to simulate clapboard, said siding elements being of uniform thickness and of greater length than width, battens secured to the sheathing in horizontal rows at intervals slightly less than the width of a siding element, said battens being slightly thicker than the thickness of a siding element, the siding elements of

each course having their upper edges butting against the battens of the next upper row and having their lower edges resting directly on and overhanging the battens of the immediate lower row.

3. An outer wall structure comprising a sheathing and a covering of fibro-cement siding elements applied in courses, battens secured to the sheathing in horizontal rows, the siding elements of each course having their upper edges secured to the sheathing adjacent to one row of battens and having their lower edges resting directly on the next lower row to cant said elements at an inclination from the vertical in simulation of clapboard.

4. An outer wall structure comprising a sheathing and a covering of fibro-cement siding elements applied in courses, battens secured to the sheathing in horizontal rows, the siding elements of each course having their upper edges secured to the sheathing adjacent to one row of battens and having their lower edges resting directly on the battens of the next lower row and overhanging and spaced outwardly from the upper edges of the siding elements of the next lower course.
